(57) **CLAIM**

The ornamental design for seating furniture, as shown and described.

DESCRIPTION

FIG. 1 is an isometric view of seating furniture, in the form of a chair, incorporating my new design;

FIG. 2 is a front elevation view thereof;

FIG. 3 is a right side elevation view thereof, the left side elevation being a mirror image;

FIG. 4 is a top plan view thereof;

FIG. 5 is a rear elevation view thereof;

FIG. 6 is an isometric view of another embodiment of seating furniture, in the form of a love seat, incorporating my new design;

FIG. 7 is a front elevation view thereof;

FIG. 8 is a right side elevation view thereof, the left side elevation being a mirror image;

FIG. 9 is a top plan view thereof;

FIG. 10 is a rear elevation view thereof;

FIG. 11 is an isometric view of another embodiment of seating furniture, in the form of a sofa, incorporating my new design, wherein the side elevation views are the same as the chair and love seat of FIGS. 1 and 6, respectively;

FIG. 12 is a front elevation view thereof;

FIG. 13 is a top plan view thereof; and,

FIG. 14 is a rear elevation view thereof.
